CASE FOR GROOMING IMPLEMENTS

Edward M. Stolarz, New York, N.Y., assignor to The Britton Corporation, Newington, Conn., a corporation of Connecticut

Filed Jan. 3, 1964, Ser. No. 78,066

Term of patent 14 years

(Cl. D87—5)

FIG 1

FIG 3

FIG. 1 is a front elevational view of a case for grooming implements showing my new design, in closed condition;

FIG. 2 is a similar view in open condition;

FIG. 3 is a rear elevational view thereof, on a reduced scale;

FIG. 4 is a right side elevational view thereof on a scale enlarged from that of FIG. 3 but reduced from that of FIGS. 1 and 2; and

FIG. 5 is a cross-sectional view thereof taken on line 5—5 of FIG. 2, on a scale enlarged from that of FIGS. 1 and 2.

The broken-line showings of grooming implements in FIGS. 1, 2, 4, and 5 is for illustrative purposes only.

I claim:

The ornamental design for a case for grooming implements, as shown and described.
